(No Model.)

L. O. MAKEPEACE.

MACHINE FOR PRODUCING STITCH IMPRESSIONS ON SOLES FOR
BOOTS OR SHOES.

No. 267,702.

Patented Nov. 21, 1882.

UNITED STATES PATENT OFFICE.

LYSANDER O. MAKEPEACE, OF WORCESTER, MASSACHUSETTS.

MACHINE FOR PRODUCING STITCH-IMPRESSIONS ON SOLES FOR BOOTS OR SHOES.

SPECIFICATION forming part of Letters Patent No. 267,702, dated November 21, 1882.

Application filed September 19, 1882. (No model.)

To all whom it may concern:

Be it known that I, LYSANDER O. MAKEPEACE, of the city and county of Worcester, of the State of Massachusetts, have invented 5 a new and useful Improvement in Machines for Producing Stitch-Impressions on Soles for Shoes or Boots; and I do hereby declare the same to be described in the following specification and represented in the accompanying 10 drawings, of which—

Figure 1 is a front side elevation, and Fig. 2 a front view, of a machine embodying my invention, the nature of which is defined in the claims hereinafter presented. Fig. 3 is a rear 15 side elevation in part. Fig. 4 is a top view of the guide-supporting bracket and the knife-carrier and its sustaining-carrier. The remaining figures are hereinafter explained.

In making leather soles for being marked 20 around the edge with what are termed by shoemakers "impression stitches," it, prior to the date of my invention, has been customary to chamfer or bevel the sole upon its hair side, where to be marked or impressed, part of the 25 grain surface in so chamfering the sole being removed with the strip taken from the sole. Soles so reduced frequently, if not always, present a rough surface or appearance in the part impressed.

30 In treating a sole by the machine hereinafter explained, such sole is bent and stitch-impressed along its edge upon the hair side of the sole, and the portion not bent down is pared, so as to cause the entire lower surface 35 of the sole to be substantially in one plane. Thus the part "stitch-impressed" is part of the hair side of the sole, and when so stitch-impressed presents a smoother and far better finish, comparatively speaking.

40 Fig. 5 denotes a top view, Fig. 6 an edge elevation, and Fig. 7 a transverse section, of a sole as prepared by the aforesaid machine.

Fig. 8 is a transverse section of a sole-blank 45 as bent on its hair side near each of its opposite edges, preparatory to being pared, or having a portion of the part bent down removed, in order to bring the entire lower surface of the sole in one plane. In this figure S is the sole-blank, A A the parts thereof bent down, 50 while e e denote the portion or strip pared off, such being triangular in transverse section.

In Figs. 1, 2, and 3, B denotes the machine-

frame, provided with a "goose-neck" or curved arm, a, to which is fixed a bracket, b, carrying the stationary guide C. Journaled in the goose-neck is a shaft, D, to be provided at its rear end with a driving-pulley. Near its front end such shaft carries the impression or marking wheel E, formed very like a spur-gear. Below the said shaft there is in the frame an arm, F, pivoted at its rear part to the frame, and having pivoted to it at its front end a conical feed-wheel, G. This arm rests upon a spiral spring, H, against the lower part of which a screw, I, screwed upward into the frame, bears. Over 65 the feed-wheel and revolving freely on the shaft D is a conic frustum or bending-wheel, K, and in advance of the "bite" of the feed and impression wheels is a paring-knife, L, which is supported by a carrier, M, pivoted to another 70 carrier, N, which in turn is pivoted to the bracket b, so as to be capable of turning in a vertical plane in order for the cutting-edge of the knife to rise or fall with the feed-wheel G as the thickness of the sole-blank may require. 75 The said knife enters a notch in a slide, D', pivoted to the arm F, a connecting-bar, O, being extended down from the said arm to the upper of two pedals, P and Q, arranged as represented, the said upper pedal resting upon 80 a friction-roller, f, carried by the pedal Q. By means of the upper pedal the feed-wheel may be moved downward away from the impression-wheel, and by means of the lower pedal such feed-wheel may be forced upward toward 85 the said impression-wheel, as occasion may require. The carrier N is provided with a set-screw, g, to act against the journal h of the knife-carrier M, the said carrier M being capable of being turned, so as to give the proper 90 inclination to the cutting-edge or front end of the knife.

In using the said machine, the sole-blank at its edge is to be laid against the guide C and introduced between the impression and feed 95 and bending wheels. The driving-shaft, being in revolution, will cause the impression-wheel to advance the blank and impress or mark it and force it against the paring-knife, which will pare it, the bending-wheel in the meantime bending down the blank so as to bring in the plane of the cutting-edge of the knife that part of the under side of the blank which is not directly underneath the impression-wheel. 100

As the sole-blank continues to advance it will be stitch-impressed about its curved periphery and pared in manner as described.

I am aware of the machines represented in the 5 United States Patents Nos. 140,035 and 150,842, the first being for bending the edges of boot and shoe soles preparatory to the sewing of welts thereto, and the second being for stitch-marking a sole and trimming it at its edge.

10 Neither of these machines has a knife arranged as in my machine to pare off a part of the bent-down portion of the sole, so as to bring the whole lower surface of such sole in one plane. Neither machine will operate to produce results 15 effected by my said machine.

I claim as my invention as follows, viz :

1. In combination with the stationary guide and the feed and the marking wheels arranged as set forth, the bending-wheel and the paring-20 knife, arranged with the said feed and mark-

ing wheels, and adapted to operate substantially as specified.

2. The combination of the pivoted or adjustable knife-carrier M, its pivoted carrier N, as described, and the knife-slide D', pivoted to the 25 arm F, with the paring-knife, the stationary guide, and the feed, bending, and marking wheels, all being arranged and to operate substantially as and for the purpose or objects set forth.

3. The combination of the two pedals P Q and the connecting-bar O with the arm F, the feed, marking, and bending wheels, and the paring-knife, all being arranged, supported, and adapted to operate substantially as set 30 35 forth.

LYSANDER O. MAKEPEACE.
